UNITED STATES PATENT OFFICE.

HARRY A. MILLS AND WILLIAM D. PYLE, OF DENVER, COLORADO.

SOUND TRANSMITTER.

Application filed January 26, 1927. Serial No. 163,638.

This invention relates to improvements in sound transmitters of the type employed in radio broadcasting.

In ordinary telephony the problem to be solved was the transmission of sounds produced by the human voice in such a manner that they would be intelligible to the listener. The range of vibrations in the human voice, during ordinary conversation, is very small and therefore the carbon microphone has been satisfactory.

Since the advent of radio broadcasting, a more difficult problem of sound transmission has been presented for solution as radio broadcasting programs include instrumental music of all kinds, together with singing by individuals and aggregations ranging all the way from duets to choirs of a hundred or more voices.

It was very soon discovered that the ordinary carbon pile telephone transmitter was not adapted to successively transmit the great variety of sounds produced in radio programs and therefore various modifications were developed and tried.

There are in common use today two types of sound transmitters for radio broadcasting work, one being a modification of the ordinary carbon pile transmitter and the other a transmitter in which the vibrating diaphragm forms one plate of a condenser.

The carbon transmitter, aside from being unsuited for transmitting the great variety of sound vibrations is also objectionable for other reasons which need not be set out in detail. It is necessary, however, to call attention to the fact that when carbon transmitters are used for transmitting operas or plays, where a large number of transmitters must be suspended about the stage, it becomes necessary to provide each transmitter with a switch and to constantly connect and disconnect the various transmitters as the singer or speaker moves about the stage.

The other type of transmitter in which the diaphragm serves as one plate of a condenser makes it necessary to resort to a high degree of amplification, as high as five stages of amplification being required. This high amplification results in distortions that are objectionable.

Where the radio program is staged at an auditorium, other than the studio forming part of the radio station, it is necessary to employ the telephone lines for making the necessary connections. With the present

microphone transmitters, it is necessary to interpose an amplifier between the transmitter and the telephone line in order to transmit the sound waves to the apparatus of the station. This makes it necessary to transport to the auditorium an amplifier, as well as the transmitter microphone.

It is the object of this invention to produce a transmitter that can be successfully employed in connection with all sound waves within the range of audibility; which can be successfully operated in parallel and which can be connected directly to the telephone lines.

Our improved transmitter briefly described consists of a stretched steel diaphragm of substantially one-thousandth part of an inch in thickness, adjacent to one side of which we support the ends of soft iron extensions which are secured to the poles of a permanent magnet. Each of the soft iron extensions have a coil of fine insulated wire, which coils are connected in series. When the diaphragm vibrates, there will be a change in the magnetic flux passing through the coils and this will set up an electromotive force whose value varies in accordance with the frequency and amplitude of the vibrations of the diaphragm. When the terminals of the magnet coils are connected to the terminals of a suitable amplifying device, currents corresponding in frequency and intensity with the sound vibrations will be produced.

In order more clearly to describe the invention and to explain its operation, reference will now be had to the accompanying drawing in which the preferred embodiment thereof has been illustrated and in which:

Fig. 1 is a side elevation of the improved transmitter, a portion of the enclosing casing being broken away to show the method of suspension;

Fig. 2 is a section taken on line 2—2, Fig. 1;

Fig. 3 is a section similar to that of Fig. 2 showing the parts to a larger scale;

Fig. 4 is a section taken on line 4—4, Fig. 3, and illustrates a detail of the construction;

Fig. 5 is a section taken on line 5—5, Fig. 2; and

Fig. 6 is a section similar to section 3 and shows a slightly modified form of construction.

The numeral 1 indicates the usual casing in which the transmitter is enclosed. This

case has a base 2 and is provided with a plurality of screened openings 3.

The transmitter has been indicated as a whole by numeral 4 and is suspended within 5 the casing by means of a plurality of coiled springs 5, which extend between eyelets 6 and 7, which are respectively secured to the transmitter 4 and the casing 1.

The transmitter consists of a metal ring 10 8, preferably of circular shape and has a central opening whose wall is threaded in the manner indicated by numeral 9. A ring 15 10 has its outer surface threaded and in engagement with the threads 9. A second ring 11, of the same diameter as ring 8, but of less thickness, is secured to the latter by means of screws 12. A diaphragm 13, which is formed from a circular sheet of steel of a thickness of about one one-thousandth of 20 an inch, has its outer edges clamped between rings 8 and 11, so as to be held firmly. The outer edge of the diaphragm is commonly corrugated so that it will offer greater resistance against movement, but this has not 25 been shown as it is old. A separator ring 14 is placed between the ring 10 and the diaphragm 13 and has the side next to the diaphragm rounded. By turning ring 10, the ring 14 will be forced against the diaphragm and distort the same in the manner 30 shown in Fig. 3. In this manner and by this means the diaphragm is stretched so that it will respond to the highest frequency sound waves that are used in music, either 35 vocal or instrumental. In order to translate the vibrations of the diaphragm into a corresponding variable electric current, we have provided a permanent magnet 15 to the poles of which we have secured soft iron 40 cores 16, each of which is provided with a coil 17. The electromagnet is placed in a casing having a bottom 18 and circular side wall 19. The magnet 15 is placed against the inner surface of the bottom 18 and is 45 held in position by an insulating filling 20, which may be sealing wax, bakelite or any other suitable insulating material that can be poured about the magnet and which will harden in place. The surface of the filling 50 is now ground so as to make it a plane. The edge of the side wall 19 and the ends of the magnet cores are also ground so that they will lie in the same plane. The outside diameter of the casing is slightly smaller than 55 the opening in the ring 11, so that it can be inserted into the latter. A paper ring 21 of a thickness of about one one-thousandth of an inch is placed between the diaphragm 13 and the edge of wall 19 and serves to 60 space the surface of the wax and the ends of the pole extensions 16 from the diaphragm. A ring 22 rests on the outside of the bottom 18 and is provided with openings for the reception of clamping screws 23,

which serve to hold the magnet casing in 65 place. The ends of coils 17 are connected to the insulated binding posts 24 from which conductors 25 extend to an amplifier, which has not been shown, a condenser 26 is connected between the binding post 24 (Fig. 2). 70

In Fig. 5, we have shown how ring 22 and the screws 23 may be dispensed with. This can be done by threading the opening in ring 11 and threading the wall 19 to correspond. The casing is then screwed into 75 ring 11.

In Fig. 2 we have shown the diaphragm thickened at 27. This is for the purpose of providing a magnetic path of greater magnetic conductivity than could be had from 80 the diaphragm alone. This thickening is attained by securing to the steel diaphragm a disk of soft iron.

When the ring 10 is rotated, it has a 85 tendency to rotate ring 14 and to prevent this, ring 14 is provided with a pin 28, which engages an opening in part 8. This is merely illustrative of a means for this purpose and any other suitable means may 90 be employed if desired.

Let us now suppose that the wires 25 are connected to some suitable amplifying device and that the diaphragm 13 is subjected to sound vibrations. The diaphragm 13 will vibrate towards and away from the ends of the magnet poles 16. This will vary the reluctance of the magnetic path and consequently the number of lines of force that pass through coils 17. The variations in the magnetic flux within coils 17 sets up an electromotive force which is transmitted by wires 25 to the amplifier. Since the diaphragm is thin and taut, it will vibrate freely when subjected to sound vibrations 100 and will set up corresponding electrical impulses in the coils 17 and wires 25. As soon as the diaphragm is removed, from the influence of the sound waves, the magnetic lines of force will set up eddy currents in the diaphragm when the latter vibrates and these will exert a retarding action which will function to stop the vibrations of the diaphragm. 110

Let us now suppose a case in which several transmitters are connected in parallel as for the broadcasting of an opera or a play. The diaphragm nearest the source of the sound will vibrate with the greatest intensity, but the current will be prevented from flowing through coils 17 of the less active transmitters because these will act as choke coils. It is therefore unnecessary to disconnect the inactive transmitters and therefore better and more satisfactory results are 115 attained.

With our improved transmitter, programs can be broadcast without making it necessary to transport an amplifier as the transmitter

wires 25 may extend to the studio, whereas with microphones now in use, this cannot be done.

A hole 29 (Fig. 3) extends through the bottom 18 of the casing and through the insulating material 20. This permits air to be displaced during the vibrations of the diaphragm.

The water proof insulating material 20 which has been shown as surrounding the electromagnets and coil 17, in addition to its function in holding the electromagnet in place, also performs another very important function, namely this, that it prevents the pole pieces 16 from vibrating and setting up sound vibrations which would interfere with the proper transmission. I have found from experience that if the magnet is secured to the casing by screws alone, or by any other clamping means, that they will vibrate and thereby deleteriously effect the operation of the transmitter. When they are embedded, as shown, in wax, shellac, bakelite or any other nonmagnetic material, this vibration is prevented and better results are obtained. The filling 20 also performs the function of providing an air chamber which is in communication with the atmosphere through the opening 29. This produces a dampening action, which prevents the diaphragm from vibrating except when subject to sound impulses.

On account of the fact that all the electrical conducting parts are thoroughly insulated and that the action of the transmitter

depends upon electromagnetic induction, this device will operate even when submerged and will not be deleteriously affected by moisture in the manner in which transmitters of other constructions are affected. 40 This property of being moisture proof is of great benefit as the operation will be constant under all conditions of humidity and the transmitter can also be used for submarine detection and other work where it is required to be immersed in liquid. 45

Having described the invention what is claimed as new is:

A transmitter for radio broadcasting comprising, in combination, a ring having its inner surface threaded, a clamping ring of substantially the same size as the first mentioned ring, a diaphragm having its outer edge located between the rings, means for forcing the rings towards each other so as to clamp the diaphragm, a third ring having its outer surface threaded and in cooperative engagement with the threaded surface of the first mentioned ring, a separator ring between the last mentioned ring and the diaphragm and means for preventing the separator ring from rotating with respect to the diaphragm whereby the latter will not be subjected to friction when the third ring is rotated. 65

In testimony whereof we affix our signatures.

HARRY A. MILLS.
WILLIAM D. PYLE.
